ROBERT ALEXANDER STEPS, OF LOS ANGELES, CALIFORNIA

SCREEN PIPE AND METHOD OF MAKING SAME

Application filed July 8, 1929. Serial No. 376,732.

The kind of screen pipe to which this invention relates is used in oil or water wells. It is placed in the oil or water bearing strata for the purpose of letting the fluid into the well while at the same time holding the sand and gravel out. To be most efficient I have discovered that such screen should have the following qualities: first, the slots should be tapered, i. e. narrower at the outside than at the inside to prevent clogging by gravel particles etc. that occasionally pass through with the oil: second, the metal should if possible be toughened at the outer entrance or mouth of the slot to reduce the abrasive action of the sand which enters with the oil: and third, the outer entrance or mouth of the slot should be depressed below the outer curved contour of the pipe so as to protect the slot while setting the screen, and prevent the formation from scraping into the slot and partially packing and sealing it. Sometimes, especially in the heavier weights of pipe or casing it is also desirable to eliminate any shoulders at the ends of the slot. This invention results in producing a screen having all the above qualities, and the novel method of producing it, as hereinafter set forth permits it to be quickly and economically produced.

Figure 1 shows the saw or circular cutter which I use in cutting the original slot. Fig. 2 is a side view of the saw. Fig. 3 shows a roller which I use in forming the slot after it is cut. Fig. 4 is a side view of this roller. Fig. 4^a shows another type of roller which can be used. Fig. 5 shows an entirely different kind of tool that can be used as a substitute for the roller. Fig. 5^a is a modified form of the tool shown in Fig. 5. Fig. 6 is a side view of the tool shown in Figure 5. Fig. 6^a is an enlarged diagrammatic view in which the curvature of the pipe is somewhat exaggerated in order to more clearly bring out the effect of the tools shown in Figs. 3, 4^a, and 5. Fig. 7 shows a piece of my finished screen pipe. Fig. 8 is a transverse section of the screen taken along the line X⁸—X⁸ of Fig. 7. Fig. 9 illustrates how I remove the shoulders from the ends of the slots.

My novel method of fabricating my screen consists in slotting the pipe 1 in any suitable

way, preferably with a circular cutter 2 as indicated in Fig. 1, at the end of which operation the side walls of the slot are parallel as shown in this figure. After this a tool having a properly formed pressure face is applied under pressure to the outside of the slot to form or forge the latter. Some of the types of tools that can be used for this purpose are shown in Figs. 3, 4^a, and 5, the characteristic of these tools being that they are so formed that when they are placed in position over the slot they first make contact with the pipe along the edges of the slot. This is best brought out in Fig. 6^a where the dotted line 3 representing the tools shown in Figs. 3 and 5, and the dotted line 4 representing the flat tool shown in Fig. 4^a, are seen to make their first contact with pipe 1 immediately at the edges 5 of the slot. When pressure is then applied to the tools in this position it sinks somewhat into the pipe and the shape of the slot changes from the straight slot 6 shown in Fig. 1 to the tapered slot 7 shown in Figs. 3, 4^a, 5 and 6^a. In view of this pressing or forging operation the metal immediately under the pressure tool is naturally compressed and is somewhat densified and toughened by the operation, this being most pronounced along the edges 5 of the slot because with tools that contact there first as above indicated, the densifying action naturally is greatest there. In other words the act of forcing the tool into the pipe in this manner to give the new slot contour shown by dotted-line 7', Fig. 6^a, produces three distinct advantages or features in the slot. First, it causes the slot to be tapered, i. e. narrower at the outside than at the inside of the pipe; second, it densifies and toughens the metal at the mouth of the slot particularly along the edges of the slot which have been depressed to 5', thereby increasing the resistance of the slot against sand abrasion; and third, the mouth of the slot between edges 5' is depressed below the outer curved contour 8 of the pipe to protect the slot against scraping itself full of dirt and clay as it rubs against the formation while being lowered into the well. These three qualities are all desirable in a well

screen, especially an oil well screen, and my above described method or process of manufacture is very effective in producing these qualities all combined as the results of the operations. For reasons previously indicated a flat tool of the general type shown in Fig. 4^a is sufficient to produce the results, and comes within the spirit of this invention. Instead of using such flat faced tools however, I prefer in practice to use tools having a convexed pressure face one form of which is shown in Figs. 3 and 5. The tool 9 shown in Fig. 3 is a hardened steel roller and pressure may be applied thereto by means of pin 10, and by means of this same pin the roller is drawn back and forth along the slot so as to form the latter as stated throughout its entire length. The tool 11 shown in Figs. 5 and 6 is not a roller, but serves as a substitute therefor. It is seen that its pressure face 12 is generally of a convex form the same as pressure face 12' of roller 9, Fig. 3. The tool 11 does not roll in the ordinary sense, and if its width is less than the length 25 of the slot then this tool is drawn back and forth along the slot as the forming process continues. Pressure may be applied to tool 11 in any suitable manner preferably an air hammer, or hand hammer. Either in roller 30 9 or tool 11, instead of the pressure face 12 being convexed in the manner shown in Figs. 3 and 5 it may be convexed along a true curve as shown in Fig. 5^a, but as above stated I prefer to use the convexed form 35 shown in Figs. 3 and 5. When this type of tool is used the slight depression formed around the slot and below the outer surface of the pipe has a neat and finished appearance as shown in Fig. 7 where these depressions are indicated by the reference numeral 40 13, the same being also truly indicated in Fig. 8.

Since the original slot was formed in the pipe by a circular saw or cutter as indicated 45 in Figs. 1 and 2, it is obvious that curved shoulders 14, see Fig. 9, will be formed at the ends of the slot. Sometimes, particularly when the pipe is very thick, it is desirable to remove these shoulders so as to give freer 50 entry for the fluid. Ordinarily the removal of these shoulders is difficult because of the narrowness of the slots, but my method makes this removal very easy. As indicated in Fig. 9 I use a double acting saw 15, in 55 which the teeth 16 along one edge are adapted to cut the adjacent shoulder during the upstroke, while the teeth 16' along the other edge are adapted to cut the other shoulder during the downstroke. Consequently by 60 reciprocating the saw, and on each stroke alternately feeding is against one shoulder or the other, the shoulders are rapidly removed until the end of the slot is either vertical, or tapered backward as indicated by 65 the dotted lines 17 Fig. 9. In Fig. 7 the

upper slot along the center line shows shoulders 14 not cut away, whereas the slot immediately below it shows the ends 17' cut away and tapered backward corresponding with dotted lines 17 Fig. 9.

In the various figures I have indicated 70 the slots as extending lengthwise of the pipe, which is the arrangement that I prefer, but the slots can obviously cut and formed crosswise of the pipe or in any other direction, without departing from the spirit of 75 this invention.

In conclusion I wish to call attention to some features of my screen which will be apparent from the previous description and 80 drawings. For instance, the depth of the depression 13 is only such that the narrowest portion of the slot, which comprises the mouth, lies nearer to the outside surface of the pipe, rather than the inside surface, al- 85 though this mouth in fact lies between these two surfaces. Also it is obvious that the depression 13 completely surrounds its slot, the perimeter of the depression being spaced apart from the slot all around, so that the 90 entire mouth of the slot, including the ends as well as the sides lies in the base of the depression, and therefore below the outside surface of the pipe. This is important and insures that neither the ends of the slot scrape 95 formation into the slot either while raising or lowering the screen through the bored well, nor will the sides of the slot scrape forma- 100 tion therein in case the screen should happen to be rotated while lowering it through the bored well. Also the use of a roller having 105 two opposed frusto-conical portions with their large ends abutting, as illustrated in Fig. 3, has an especial advantage in that when the center of such roller presses at the ex- 110 tremities of the slots, its curved circumferential shape causes it to press into the unslotted part of the pipe at places beyond the ends of the slots and in line with the slots including 115 that portion that lies between the projected parallel side walls of the slots, assuming that these side walls are so theoretically project- 120 ed beyond the ends of the slots. This is all clear from previous descriptions herein set forth, taken in connection with the drawings, and illustrates how the entire slot, including the extreme ends as well as the side walls thereof, is depressed below the outer surface 125 of the pipe, to give the good results previous- 130 ly described.

I claim:

1. The method of making screen pipe consisting of slotting the pipe with a circular cutter operating from the outside surface of the pipe inward, also removing the shoulders at the ends of the slot by a double acting reciprocating tool adapted to cut one shoulder on the forward stroke and the other shoulder on the return stroke, and also drawing a roller back and forth under pressure over the

outside of the slot and lengthwise thereof, said roller comprising two opposed frusto-conical portions with their large ends abutting so that when the center of said roller works at the extremities of said slot it presses into the unslotted part of said pipe at places beyond the ends of said slot and between the projected side walls thereof.

2. The method of making screen pipe consisting of slotting the pipe with a circular cutter operating from the outside surface of the pipe inward, and then removing the shoulders at the ends of the slot by a double acting reciprocating tool adapted to cut the one shoulder on the forward stroke and the other shoulder on the return stroke.

3. The method of making screen pipe, consisting of slotting the pipe with a slot having parallel side walls, and subsequently drawing a roller back and forth under pressure over the outside of the slot and lengthwise thereof, said roller comprising two opposed frusto-conical portions with their large ends abutting so that when the center of said roller works at the extremity of said slot it presses into the unslotted part of said pipe at places beyond the ends of said slot and between the projected side walls of the slot.

4. Screen pipe consisting of pipe having elongated slots the narrowest portion of each slot comprising a toughened mouth lying between the inner and outer surfaces of said pipe but nearer said outer surface, said pipe also having pressure-formed depressions in its outside surface one completely surrounding each of said toughened slot mouths respectively, the perimeter of each of said depressions lying in the outside surface of said pipe and being completely spaced apart from its slot and completely surrounding its slot, the said depression becoming deeper all around its slot from the perimeter of said depression toward the slot so that the entire mouth of the slot including its ends as well as its sides lies below the outside surface of said pipe.
